United States Patent Office

Des. 186,148
Patented Sept. 15, 1959

186,148

WRITING INSTRUMENT

Robert W. Schier, Evanston, Ill., assignor to The Parker Pen Company, Janesville, Wis., a corporation of Wisconsin

Application August 29, 1958, Serial No. 52,443

Term of patent 14 years

(Cl. D74—17)

Fig. 1 is a rear elevational view of a writing instrument embodying my new design;

Fig. 2 is a side elevational view thereof;

Fig. 3 is a front elevational view thereof; and

Fig. 4 is a top plan view thereof taken from line 4—4 in Fig. 3.

The essential features of the design reside in the portions shown in solid lines on the drawing.

I claim:

The ornamental design for a writing instrument, as shown and described.
